UNITED STATES PATENT OFFICE.

GEORGE P. FENNER, OF NEW LONDON, CONNECTICUT

PRINTING-PRESS.

SPECIFICATION forming part of Letters Patent No. 604,974, dated May 31, 1898.

Application filed April 29, 1897. Serial No. 634,435. (No model.)

To all whom it may concern:

Be it known that I, GEORGE P. FENNER, a citizen of the United States, residing at New London, in the county of New London and State of Connecticut, have invented new and useful Improvements in Printing-Presses, of which the following is a specification.

By means of this invention the parts of a printing-press are made readily accessible, as for repairing, cleaning, or for other purposes; and the invention resides in the novel features of construction set forth in the following specification and claims, and illustrated in the annexed drawings, in which—

15 Figure 1 is a side elevation of a printing-press. Fig. 2 is a plan view of Fig. 1. Fig. 3 is a side elevation of portion of a printing-press with parts in a different position than in Fig. 1. Fig. 4 is a section along line *x* *x*, Fig. 20 20. Fig. 5 is a detail view of a connection between the carriage-actuating rack and lever. Fig. 6 is a section along line *y* *y*, Fig. 5. Figs. 7, 8, and 9 show a modification. Fig. 10 is a sectional side elevation of the delivery mechanism, looking from the side opposite to that shown in Fig. 7, the tape-carriage being at the impression-cylinder; and Fig. 11 is a similar view showing the tape-carriage moved or run away from the impression-cylinder. Fig. 30 30 12 is a detail view illustrating the means for controlling the operation of the rolls *H* *H'* and *L* *M*.

The frame or support is shown at *A*, and a sheet fed off delivery-board *B* and taken by 35 grippers on impression-cylinder *C* is carried between the latter and the type-bed *D*, after which the tape-carriage *E* by its tapes carries the sheet to a receiving board or table. The operation of these devices may be of any suitable kind.

The carriage by its wheels 1 and 2 runs on tracks. Each track is composed of sections 3 and 4. The track-sections 3 are fixed or secured to frame *A*, and the track-sections 4 are movable on or along sections 3. These 45 track-sections can be suitably connected, as by tongue-and-groove or pin-and-slot connection 5 and 6. The track-sections 4, having track 7 engaged by gear-wheel 8, actuated by handle or crank 9, said sections 4 can be readily run away from cylinder *C*, Fig. 3, or to-

ward said cylinder, Fig. 1, to enable the carriage to run or reciprocate to and from such cylinder. The carriage *E* having been run away from the cylinder, Fig. 3, and the track-sections 4 slid or moved away from such cylinder the latter is made readily accessible when required.

The carriage *E* is actuated or reciprocated by its racks or rack 10 being engaged by gear-wheel 11, driven by gear-wheel 12, engaged by rack 13, forming part of rod 14. This rod 14 is detachably connected, as by its hook or hooked end 15, to stud 16 on arm 17 of the lever 18, fulcrumed at 19. The lever-arm 18 is 65 jointed at 20 to link 21, jointed at 22 to the crank 23, reciprocating said link 21.

The outer or free end of stud 16 has a head 24, Fig. 6, on which slides a sleeve 25, the motion of which is limited by its slot 26 being engaged by screw 27, for receiving which the head 24 is suitably tapped. When the hook 15 of rod 14 is slipped onto stud 16 and the sleeve or collar 25 has been slipped over the hook 15 against or toward rod 14 and secured by the tightening of screw 27, said hook 15 is held against disengagement from stud 16, but the circular collar 25 leaves the hook 15 free to turn or swing on said stud. A loosening of screw 27 and slipping back of 80 collar 25 leaves hook 15 free to be disengaged from stud 16.

An advantage of the sectional or telescoping track 3 and 4 is that when the sections 4 are slipped along sections 3 away from cylinder *C* said sections 4 lie alongside of fixed sections 3 and no part of the track projects beyond the machine-frame. In case the track-sections 3 and 4 were in one piece or secured together and movable the moving of the track 90 away from the cylinder *C* would cause a portion of the track to slide or project outside of the machine-frame, which might cause annoyance, as in a small space or factory or by blocking a passage.

By having the rack 13 14 readily disconnecting from lever-arm 17 the carriage *E*, for example, after having been run away from the cylinder *C* can be left at rest or undisturbed while other parts of the press are undergoing examination, repair, or tests.

The carriage-wheels 1 and 2 on each car-

riage side, as seen in Fig. 2, are out of alignment to properly engage or run respectively on track-sections 3 and 4.

When running at very high speed, it has been found that the sheets will slide ahead on tapes F, Fig. 8, of the tape-carriage E instead of stopping in the right position when making the first stop. To prevent such misplacing or sliding, stops or fingers 28 are provided, which when dipped or inserted between the tapes will arrest the sheet in proper position. These fingers 28 are suitably shaped or bent, as seen in side view in Figs. 7 and 9, and are suitably or adjustably secured, as by screws or fastenings 29, to a rock-shaft 30. This shaft is rocked by arm or lever 31, having a roller 32, (seen in plan view in Fig. 8,) and made to rest on what may be called a "wedge" cam or rail, moving with or secured to the tape-carriage E, and having a high portion 33 and a lowering or inclined or wedge portion 34, as seen in Fig. 7. When the tape-carriage E approaches the end of its travel or stroke away from the cylinder C, the roller 32, being made to rest or drop along the incline 34, will dip the free or depending portions of fingers 28, so that at the time the carriage ends its outward travel away from cylinder C and begins its return stroke toward the cylinder the stop or fingers 28, dipping to or between tapes F, will arrest the sheet in adjustment to be properly delivered as the carriage returns. The return of the carriage-raising roller 32 up incline 34 and onto the high part 33 of the rail will cause the fingers 28 to rise out of the path of the sheet to be delivered off the tapes.

The rollers M and L, it is noticed, are mounted on a track-section, and during the printing and delivery these rollers M and L remain a constant distance from cylinder C, as seen in Figs. 10 and 11. The rollers H' and H are mounted on and reciprocate with the carriage E. These rollers H, H', L, and M are normally at rest, being rotated by the movement of the endless tapes F, which tapes in their turn are actuated by the carriage E as the latter reciprocates.

When the carriage travels forward from the position shown in Fig. 10 to that shown in Fig. 11, the roll H travels away from roll M and the roll H' travels toward or approaches roll L. During such forward travel of the carriage the roll H does not rotate; but the roll M does rotate as a tape portion from the shortened distance H' to L travels about said roll M to fill the enlarged span M to H. During the return of the carriage the roll M does not rotate and a sheet resting on the tapes close to said roll M remains at rest. During said return, however, the rolls H and H' do rotate and a second sheet resting on the tapes close to roll H and over the delivery-table drops onto such table as the outer portion of the tapes passes back from under said sheet. In other words, when the parts are in the position shown in Fig. 11 there are two sheets on

the tapes, one in outer position over the delivery-table and a second sheet in inner position near roll M. On the return of the carriage the outer sheet is dropped onto the delivery-table, while the second or inner sheet stands still. When the carriage again runs forward, this second sheet is carried out over the delivery-table, while a third sheet runs from cylinder C to come to rest with its tail edge close over roll M. The return of the carriage to the cylinder will not move or affect the position of this third sheet just fed, as described; but such returning carriage by incline 34 and rail 33 will move and hold stop 28 out of the path of such third sheet just fed. The next stroke of the carriage away from cylinder C will carry such third sheet out or away from the cylinder and beyond stop 28 and into position for delivery upon a receiving-table, so that when the carriage now returns to the cylinder and the sheet-sustaining portion of the tapes draws away under said third sheet so carried out the latter drops onto a receiving board or support.

The rails which comprise the movable track-section are of a length greater than the space between the fixed rails and the impression-cylinder, so that when the movable rails are run to the cylinder said movable rails partly overlap or are held by said fixed rails. The carriage has its wheels 1 arranged to run on the fixed rails and its wheels 2 arranged to run on the movable rails, so that when the carriage has been run away from the cylinder the movable rails can be moved along under the carriage away from the cylinder without disturbing such carriage.

By suitably-applied ratchets and pawls, as seen in Fig. 12, the rollers H, H' can be prevented from rotating in the outward movement of the carriage E, while the rollers L, M do rotate, and the first-mentioned rolls can be allowed to rotate in the return movement of the carriage, while the latter rolls are held against rotation.

Suppose the rollers M, H, H' to be provided with ratchets and pawls, allowing such rollers to respectively rotate only in the direction of the respective arrows m , h' , h . On the outward travel of the carriage the roller H pulls on the tape portion running to this roller H from roller M. The tendency of this pull is to rotate roller M in the direction of arrow m , and, as seen, the roller M is free to rotate in this direction. Such pull, however, cannot rotate the roller H in the direction opposed to either arrow h or m , as the pawl of roller H prevents such rotation.

On the return of the carriage the roller H pulls on the tape portion running about roller L to roller M, and such pull tends to rotate roller M in the direction opposed to arrow m , or, in other words, causes the roller M to be locked or held stationary against its pawl, so that the tape portion running about roller M remains at rest during the return of the carriage.

What I claim as new, and desire to secure by Letters Patent, is—

1. An impression-cylinder and a type-bed, combined with a tape-carriage, and a sectional track or way for the carriage, one of the track-sections comprising rails fixed at a distance from the cylinder and the other track-section comprising rails slidably mounted alongside the fixed rails and of a length greater than the space between said fixed rails and the cylinder, so that when the movable rails are run to the cylinder said movable rails partly overlap or are held by said fixed rails, and said carriage having wheels arranged to run, respectively, on the fixed and movable rails, so that when the carriage has been run away from the cylinder, the movable rails can be moved along under the carriage away from the cylinder without disturbing such carriage, substantially as described.
2. An impression-cylinder and a type-bed, combined with a tape-carriage, a hooked actuating-rod for the carriage, an actuating-lever having a stud provided with a head and made to receive said rack-hook between said head and lever, a sleeve slidably mounted on the head and adapted to move toward and
3. An impression-cylinder and a type-bed, combined with stop-fingers, a carriage made to pass from the cylinder under the fingers and beyond the latter, and tapes actuated by the carriage so as to be extended from the impression-cylinder under and beyond the fingers and to receive a sheet fed from the cylinder and then to carry said sheet into position for delivery from the tapes, said stop-fingers being made to dip between the tapes after the latter have been extended under and beyond the fingers, and arranged to arrest a sheet on the tapes after such sheet has been fed from the impression-cylinder and prior to its advance into position for delivery from the tapes, substantially as described.

In testimony whereof I have hereunto set my hand in the presence of two subscribing witnesses.

GEORGE P. FENNER.
